UNITED STATES PATENT OFFICE

169,582

COMBINED FUNERAL AND FLOWER CAR

Robert D. Ehret, Hato Rey, P. R.

Application July 1, 1952, Serial No. 20,435

Term of patent 14 years

(Cl. D14—17)

To all whom it may concern:

Be it known that I, Robert D. Ehret, a citizen of the United States, residing in Hato Rey, Puerto Rico, have invented a new, original, and ornamental Design for a Combined Funeral and Flower Car, of which the following is a specification, reference being had to the accompanying drawings, forming a part thereof, wherein:

Figure 1 is a side elevation partially in perspective of a combined funeral and flower car, showing my new design;

Figure 2 is a rear elevation with the rear door closed;

Figure 3 is a rear elevation with the casket door and the flower door open; and

Figure 4 is an isometric perspective of the vehicle.

The dominant features of my design are shown in full lines and more particularly in the flower tray and its relationship to the elongated side and rear windows.

I claim:

The ornamental design for a combined funeral and flower car, substantially as shown and described.

ROBERT D. EHRET.
